UNITED STATES PATENT OFFICE.

ISHAM D. FULLER, OF CHICAGO, ILLINOIS, ASSIGNOR, BY MESNE ASSIGNMENTS,
TO THE FULLER WATCHMAN'S ELECTRICAL DETECTOR COMPANY, OF
SAME PLACE.

WATCHMAN'S TIME-RECODER.

SPECIFICATION forming part of Letters Patent No. 443,435, dated December 23, 1890.

Application filed July 2, 1890. Serial No. 357,573. (No model.)

To all whom it may concern:

Be it known that I, ISHAM D. FULLER, of Chicago, in the State of Illinois, have invented certain new and useful Improvements in 5 Watchmen's Time-Recorders, of which the following is a specification.

My invention relates to improvements in watchmen's time recorders or systems in which an ordinary clock mechanism provided 10 with a revolving detachable paper dial is used in conjunction with electro mechanism, in electrical connection with the several stations in the watchman's beat and adapted to record on such dial the watchman's visits to 15 said stations by the application of a circuit-closing key applied by the watchman to circuit-closing mechanism at such stations; and the objects of my improvements are, first, to provide a construction for the electro-mechanical part of the apparatus whereby the 20 number of stations in any given embodiment of the system may be varied or increased with greater facility than heretofore; second, to provide automatic electrical switches, in 25 connection with the electro-mechanical part of the apparatus and some point in the beat, whereby a single electric circuit is made to embrace all of the stations in the beat, and, third, to provide improved means for recording 30 the watchman's visits to the stations on the paper dial. I have attained these objects in the apparatus constructed as illustrated in the accompanying drawings, in which—

35 Figure 1 is a front elevation of the electro-mechanical part of the apparatus. Fig. 2 is a transverse vertical section on the line 2 2 of Fig. 1. Fig. 3 is a top or plan view of the electro-mechanical part of the apparatus. 40 Fig. 4 is a vertical section on the line 4 4 of Fig. 3, looking in the direction of the arrows. Fig. 5 is a detail showing in perspective a detached piece of the electro-mechanical part of the apparatus. Fig. 6 is a front elevation 45 of the apparatus entire, showing the relative position of the parts and the electrical connections. Fig. 7 is a detail showing in side view the clamp for holding the disk to the hour-hand shaft of the clock.

In the drawings, A designates the frame 50 for supporting the separate line-sections of the electro mechanism with which the separate lines or circuits are connected. This frame consists of a rectangular piece or plate provided with screw-holes a for attaching it 55 to the clock-casing, and screw-holes a' for attaching said separate line-sections thereto.

B designates the separate line-sections. These are composed of the front piece b, the end pieces b', and a central stirrup b², which 60 parts are preferably all cast as one piece. The end pieces b' have a foot-piece b³, provided with a screw-hole, whereby said line-sections B are attached to the frame A. The screw-holes in said frame A are so placed as 65 to make the line-sections B fit closely together in contact and fill the entire area of said frame, when as many are placed thereon as the same is designed to hold, and any of said line-sections can be removed from said frame 70 by taking out the screws in the foot-pieces b³ without disturbing any of the others.

C designates the electro-magnets, which are secured to the line-sections B by means of screws C', passing through the front piece b and 75 into the magnet-core c in such manner as to hold the same firmly to the respective line-sections. One end of each magnet-wire c' is attached permanently to the line-section at c² by being soldered thereto, so that each line-section is made a part of the electric circuit. 80 The other end of each magnet-wire is connected with a binding-post D at each end of said line-sections, being connected thereto by an insulating-piece D', secured to a projection d, cast on the end pieces b' of the line-sections. Supported in the stirrup b² of each line-section there are preferably two sliding spring-pressed bars b⁴, provided each with a different embossed or indented type or die on 85 its front end designed to indicate a different station on the watchman's beat. The springs of said bars hold them normally retracted, so that their rear ends are projected through the stirrup. To the side pieces b' are pivoted the 90 armatures E, adapted to strike the rear ends of the bars b⁴ when the circuit is closed on the magnets C, or any one of them, there being a 95

spring adapted to retract the armatures when the circuit is open and keep them normally off the bars b^4 .

The frame A is provided with a rubber or other insulating piece F, for the armatures to rest against in their normal position.

To the top line-section is attached a bar or plate G, whose inner surface is provided with sunken or embossed type or dies g , corresponding in kind and position with type or dies on the spring-bars b^4 .

I prefer to put the male or embossed type or dies on the type-bars and the female or indented type or dies in the bar or plate G, as shown in the drawings.

The bar or plate G is extended down in front of the line-sections in a plane parallel with the front of the type-bars, so that as any of said type-bars are pressed forward by a blow 20 of the armature on the rear end thereof the type on the front end will be forced into or upon its corresponding type in the bar or plate G.

The electro-mechanical part of the apparatus, as in the present instance shown and described, is for a ten-station apparatus, and has but three of the lines shown as connected in circuit, the rest being represented in blank.

I do not consider that it is essential to the 30 invention embraced by this part of the apparatus to employ two electro-magnets and two type-bars in each line-section, as shown, nor that the particular arrangement of magnets and armatures shown for operating said type-bars should in any case be followed.

From the description thus far given it is obvious that other stations might be added by removing any of the blank line-sections B, as shown in the lower portion of Figs. 2 and 4, 40 and substituting in its place a line-section having one or both magnets and armatures with wire connections, as shown in the upper portion of said figures.

The frame with detachable line-sections, as shown, with the sections all full or partly full and partly blank, to suit the number of stations in the watchman's beat in any individual case, is placed in the clock-casing above the clock-movement in the ordinary way, the 50 position of the clock relatively thereto being shown by dotted lines II II in Fig. 6. In this position the paper dial I, attached to the hour-hand shaft I' of the clock, may have its upper half revolved by the clock-movement between the bar or plate G and the front of the line-sections, so that when the circuit is closed at any station on the watchman's beat, as hereinafter described, the armature will drive the type-bar b^4 of that station forward against 55 the bar or plate G, and by indenting or pinching the paper print or cut out the number or other character employed to designate the station upon said dial. On the dial, as shown, the radial full lines indicate the hours and 60 the half and quarter radial lines indicate fractions of an hour. Said dial is slowly revolved in the direction of the arrow as the hour-hand

of a common clock, so that the time of the watchman's visits to the various stations of his beat may be read on the dial by observing the position of the imprint on the dial relatively to said radial line. I have provided means for attaching said dial to the hour-hand shaft of the clock by a yielding attachment, which will be sufficient to keep the dial 70 in motion with the said shaft under ordinary circumstances; but in case the dial should accidentally become fastened to the other part of the apparatus, so as to prevent its rotation, its connection with said shaft will yield and 75 allow the clock to go on without tearing the dial. This consists in an inner plate i and an outer spring-pressed plate i' . Said plate i is provided with a socket-piece i^2 , adapted to fit over the end of said hour-hand shaft so as to 80 secure said plate rigidly to said shaft. On the opposite side of said plate from the socket-piece is a piece i^3 , which is screw-threaded at the outer end and forms, when in place, an extension of the hour-hand shaft beyond said 85 plate i . The dial is made with a perforation in the center adapted to just fit over this extension, and the spring-plate i' is then placed over the dial and the nut i^4 is tightened down, so as to revolve with the hour-hand shaft. The 90 nut i^4 has a groove or shoulder i^5 , which engages the spring i^6 of the plate i' , for the purpose of clamping said plate down on the dial in such manner as to cause the dial to revolve with the hour hand shaft and permit it to be 95 stopped by slipping between said plates in case it should be caught and held fast near the periphery by any force which would tear it if rigidly secured to the hour-hand shaft.

The switch mechanism is shown in Fig. 6, 105 the upper part of which shows said switch mechanism in front elevation, and the lower part shows it in rear elevation with a portion of the switch-board broken away. Said switch mechanism consists of a base piece or 110 plate K, upon which is mounted an electro-magnet L, with its armature l, said armature being held normally retracted by a spring l' . To the extreme end of the armature is pivoted a spring-pressed ratchet hook or catch 115 l^2 , which is adapted to engage teeth or projections m on a revolving disk M. This disk is mounted on a shaft m' , which is journaled in a post or standard M', attached to the base-piece K. Behind said disk and supported on 120 said standard is the switch-board N, made of hard rubber or other insulating material. The switch-board is provided with a series of metallic sections n , preferably arranged in a circular path, and the branch wires from the 125 several line-stations are attached to these metallic sections at one end of the main line and with the watchman's station at the other end.

The revolving disk M is provided with a 130 switch arm or projection n' , which is attached to the shaft m' , and has its outer end adapted to move in contact with said metallic section and close the branch circuit at that point

with the wire which is connected to said metallic section.

Attached to the face of the switch-board is a ratchet m^2 , which engages a pawl pivoted to the switch-arm and adapted to engage said ratchet and prevent said disk and its switch-arm from turning backward. The electrical connection is made through the wires 1 and 2. The binding-post o on the lower line-section 10 is in electrical connection, through the contact of said several line-sections with each other, with the coil-wires of all of the magnets C by means of the connections at c' , and thence through said wires with the several insulating binding-posts D. The wire 1 extends from said binding-post o by branches 3 4 5, &c., to the various watchmen's stations P, thence through open circuit at said watchmen's stations, provided with ordinary key-circuit-closing mechanism, to the switch-board on the premises to be watched, being shown at the bottom of Fig. 6, thence through the switch-arm n' to the shaft m' , thence to the magnets I, and thence to the battery. The wire 2, starting from the battery, runs to the magnets L of the switch mechanism at the registering-instrument, being the one shown at the top of Fig. 6, thence to the shaft m' , thence through the switch-arm n' to the metallic sections n, and thence by branch wires 3^a 4^a 5^a, &c., to the insulating binding-posts D.

As shown in the drawings, the circuit is closed through the wires 1 and 2 and their respective branches 3 at all points except P on the branch 3 of the wire 1. By closing the circuit at this point by the application of the watchman's circuit-closing key a current would be sent over said circuit which would simultaneously operate one of the armatures E on the second line-section B from the top of frame A and both of the armatures l of the switch mechanisms. The first-named armature E would strike the bar b^4 , bearing the type 3 and corresponding with the type 3 on the bar or plate G and print the station 3 on the dial. The armatures l of the switch mechanisms would draw down the spring-pressed ratchet-hooks l^2 into engagement with the projection m on the disk M, and the withdrawal of the circuit-closing key would permit the retraction of said ratchet by the spring l' , which would move the switch from contact with the metallic section with which the branch wires 3 are connected to and into contact with the metallic section to which the branch wires 4 are connected in both switch mechanisms.

Having described my invention, what I claim, and desire to secure by Letters Patent, 60 is—

1. In a watchman's time-recorder, the sections B, each made as an integral and separate part of the apparatus, and composed of a metallic front piece or plate provided with the end pieces or supports, an electro-magnet with one end of its coil connected electrically with said front piece and the other end con-

nected non-electrically therewith, a sliding bar, and an armature adapted to operate the same, said supports and operating parts being attached to the rear of said front piece, as and for the purpose specified.

2. In a watchman's time-recorder, and in combination, a frame, as A, adapted to be secured to the interior of a clock-casing and provided with a series of regularly-arranged holes a, and a series of line-sections, as B, each made as an integral part of the apparatus, and composed of a metallic front piece b, one or more electro-magnets with one end of the coil electrically connected with said front piece and the other non-electrically connected therewith, one or more sliding spring-pressed bars, and one or more armatures for separately operating the same, said separate line-sections being adapted to be separately connected with and disconnected from the frame, as and for the purpose specified.

3. In a watchman's time-recorder, and in combination, a series of sliding spring-pressed bars, each provided with a different type or die, a bar or plate arranged opposite to said type-bars and provided with companion type or dies severally corresponding in character and relative position with the type of said bars, and electro mechanism for separately operating said respective type-bars from different stations, substantially as specified.

4. A watchman's time-recorder system comprising a switch-board within the beat, branch wires connecting the various stations of the beat in open circuit with said switch-board, an electro-mechanical switch, substantially as shown, for changing the connection of said branch wire through said switch-board by the closing and opening of the circuits at said stations, a registering apparatus having electro-mechanical registering appliances for each station in the beat, a switch-board in conjunction with said registering apparatus, branch wires for connecting each of said electro-mechanical registering appliances with said switch-board, an electro-mechanical switch for changing the connection of said branch wires through said switch-board, and the main circuit-wire, as the wires 1 and 2, for connecting a battery, said two switch mechanisms and the registering apparatus through said branch wires, substantially as shown and described.

5. In a watchman's time-recorder or analogous system, and in combination, a switch-board provided with metallic sections for attaching the various lines of the system, a revolving switch-arm in connection with said sections, and electro mechanisms having an armature provided with a spring-pressed ratchet-hook adapted to automatically engage the switch-arm by the closing of the circuit and to shift the switch by the recoil of the armature, substantially as specified.

6. In a watchman's time-recorder, the spring-clamp for attaching the paper dial to

the clock-movement, consisting of the plate *i*, having a socket on one side for attaching said plate to the hour-hand shaft, and an extension-piece on the opposite side screw-threaded at its outer end, the plate *i*, provided with the spring *i⁶*, and the nut *i⁴*, provided with a groove or shoulder adapted to said spring,

substantially as and for the purpose specified.

ISHAM D. FULLER.
